United States Patent Office

Des. 192,349
Patented Mar. 13, 1962

192,349

VEHICLE DOOR HANDLE

George W. Walker, Bloomfield Hills, Mich., assignor to Ford Motor Company, Dearborn, Mich., a corporation of Delaware

Filed Oct. 3, 1960, Ser. No. 62,359

Term of patent 7 years

(Cl. D10—8)

FIG. 3

FIG. 2

FIG. 4

FIG. 5

FIG. 1

FIG. 1 is a perspective view of a vehicle door handle embodying my new design;

FIG. 2 is a side elevation;

FIG. 3 is a plan view;

FIG. 4 is a sectional view taken substantially through line 4—4 of FIG. 2; and

FIG. 5 is a sectional view taken substantially through line 5—5 of FIG. 2.

I claim:

The ornamental design for a vehicle door handle, as shown.
